[57] CLAIM

The ornamental design of a cereal bowl, as shown and described.

DESCRIPTION

FIG. 1 is a perspective view of a cereal bowl showing the first embodiment of my new design;

FIG. 2 is a front elevational view of the cereal bowl of FIG. 1, the opposite side being identical;

FIG. 3 is a right side elevational view of the cereal bowl of FIG. 1, the opposite side being identical;

FIG. 4 is a top plan view of the cereal bowl of FIG. 1;

FIG. 5 is a bottom plan view of the cereal bowl of FIG. 1;

FIG. 6 is a perspective view of a cereal bowl showing the second embodiment of my new design;

FIG. 7 is a front elevational view of the cereal bowl of FIG. 6, the opposite side being identical;

FIG. 8 is a right side elevational view of the cereal bowl of FIG. 6, the opposite side being identical;

FIG. 9 is a top plan view of the cereal bowl of FIG. 6;

FIG. 10 is a bottom plan view of the cereal bowl of FIG. 6;

FIG. 11 is a perspective view of a cereal bowl showing the third embodiment of my new design;

FIG. 12 is a front elevational view of the cereal bowl of FIG. 11, the opposite side being identical;

FIG. 13 is a right side elevational view of the cereal bowl of FIG. 11, the opposite side being identical;

FIG. 14 is a top plan view of the cereal bowl of FIG. 11;

FIG. 15 is a bottom plan view of the cereal bowl of FIG. 11;

FIG. 16 is a perspective view of a cereal bowl showing the forth embodiment of my new design;

FIG. 17 is a front elevational view of the cereal bowl of FIG. 16, the opposite side being identical;

FIG. 18 is a right side elevational view of the cereal bowl of FIG. 16 the opposite side being identical;

FIG. 19 is a top plan view of the cereal bowl of FIG. 16; and,

FIG. 20 is a bottom plan view of the cereal bowl of FIG. 16.
